DRAPERY PINHOOK PACKAGING AND DISPENSING DEVICE

BACKGROUND

1. Field of the Invention

This invention relates to the application of drapery pinhooks to draperies and more particularly to tools containing a supply of stacked pinhooks to be successively dispensed therefrom and held by the tool for application to the drapery.

2. Description of Prior Art

Heretofore such tools have been expensive in fabrication and assembly and have required special skill in operation. For example in the Niel Pat. No. 3,332,598 there is a rack of complicated shape, having transversely extending ribs, a pin to hold the stack together and a hook to lock that rack inside of a rectangular box. The box does not confine the exterior of the pinhooks, but instead may allow the pinhooks to tilt, cross each other and get stuck.

SUMMARY

The present invention of the Drapery Pinhook Packaging and Dispensing device comprises a tube having an interior cross section conforming generally to the exterior periphery of the pinhooks, thereby to facilitate loading, dispensing or removal thereof. The tube is preferably of extruded plastic and contains an integral supporting member having at least a pair of longitudinally extending flanges with contact portions spaced from the inside surface of the tube to receive the drapery pinhooks therebetween. The interior cross section is a unitary continuous surface and thus of uniform cross section from end to end, and free of transversely extending parts. Preferably the tube has a dispensing head or cap at each end thereof, of complementary construction for respective right-hand or left-hand operation.

DRAWINGS

FIG. 1 is an exploded perspective view of a drapery pinhook packaging and dispensing device, according to the preferred embodiment of the present invention;

FIG. 2 is a transverse view taken along line 2-2 of FIG. 1;

FIG. 3 is a perspective view showing the same held for right-hand operation;

FIG. 4 shows a drapery pin engaged by the positioner; and

FIG. 5 is an end perspective view of a right side dispensing head.

DETAILED DESCRIPTION

As shown in the drawings, the preferred form of the device comprises a tube 10 having a wall 12 of integral construction and uniform thickness in cross section throughout its length.

The tube 10 is drawn plastic or aluminum by extrusion.

The wall 12 has a bevel or sloping portion 15, which with the rest of the tube is shaped to conform to the exterior of the pinhook portion 17 of the pinhook.

Inside the tube 10 is a supporting member 14 comprising an inwardly extending horizontal flange 16, in turn having an upwardly extending vertical flange 18 and a downwardly extending vertical flange 20. These flanges form longitudinally extending ridges spaced from the inside surface of the tube 10 to receive the drapery pinhooks between the supporting member 14 and the tube 10. The pin portion 20 of the pinhook fits snugly under the horizontal flange 16. Thus the supporting member 14 has a uniform cross section throughout its length and is integral with the tube 10, all in one piece.

As shown in FIG. 2, the inner surface of housing 10 conforms to the outer surfaces of the curved pinhook while the supporting ledge 14 and the flanges attached thereto provide surfaces conforming to the inner surfaces of the curved pinhook. Accordingly, the interior cross section area of the tube 10 conforms to the entire exterior periphery which periphery includes both the inner and outer curved surfaces of the pinhook.

The clearance between the pinhooks and the tube 10 and supporting member 14 is small enough to maintain the pinhooks in alignment during the entire dispensing operation.

The end of tube 10 fits into a dispensing head 36 with vertically slideable therein a positioner 24 which receives the pinhooks in succession by gravity from tube 10. The positioner 24 is operated by a thumb piece 26 against a return spring 28 bearing on the angle bottom 30 of the housing 22.

As shown in exploded form in FIG. 1 and in more detail in FIGS. 4 and 5, the positioner 24 is maintained in slideable relationship with the end of tube 10 by housing 22 and angle plate 30, which angle plate also serves as a stop for the vertical travel of positioner 24. Thus, when the positioner 24 is in its most upward position, being urged into that position by spring 28 exerting an upward force thereon, the positioner lip 40, which lip has the same general shape as the inner periphery of the pinhooks, engages a first pinhook positioned in the tube 10. When downward force is exerted on thumb piece 26, the positioner 24 moves downward inside housing 22. Accordingly, the bottom leg of the engaged pinhook is also moved downward and thus emerges below the base line of the tube 10. At this point the hook is maintained in rigid relationship to the tube 10 and is in position to be inserted into the drapery material. Once the drapery hook is so engaged, the pressure is removed from the thumb piece 26 and the positioner 24 again moves upward, thereby leaving the engaged pinhook in the drapery material. It should be noted that the downward distance through which the engaged pinhook is moved is relatively small and is determined by the thickness of the bottom edge of the tube 10.

FIG. 5 illustrates a dispensing head arranged for connection to the right end of the tube. Lip 40 of positioner 24 is shown gripping a pinhook (shown in broken lines) prior to displacement of the pinhook downward.

Pilot screws 32 passing through registering holes in the housing and positioner, engage threaded sockets 34 in the bottom 30 to hold these parts together and maintain them in alignment.

40 The other end of the tube 10 is provided with a complementary dispensing head 36 adapted for left-hand operation.

In either case the other end of tube 10 will be closed by cap 38 as shown in FIG. 3. The tube 10 is loaded with pinhooks as a retail package and a cap 38 is applied to each end as a closure.

45 For use in applying the pinhooks to the drapery, one of the caps is replaced by a dispensing head 36 and fastened to the tube 10 by a clamp 37 which is an integral part of the dispensing head housing.

50 I claim:

1. A drapery pinhook packaging and dispensing device comprising a package tube for supplying a plurality of pinhooks;

55 a dispensing head into which said pinhooks may be passed from said tube; a pinhook positioner mounted in said dispensing head for receiving said pinhooks from said package tube; said package tube having an interior cross section defined by the inner wall of said package tube and a ledge integral with said package tube, said interior cross section conforming to the exterior periphery of the pinhooks, thereby to facilitate storage and passing said pinhooks from said tube.

60 2. A drapery pinhook packaging and dispensing device as claimed in claim 1, wherein said integral ledge comprises at least a pair of longitudinally extending flanges each spaced in fixed relationship with the inside of said tube to receive said drapery hooks between said ledge and said tube.

65 3. A drapery pinhook packaging and dispensing device as claimed in claim 2, in which said integral ledge is of uniform cross section from end to end, so as to define a continuously uniform passageway for the passing of said drapery pinhooks.

70 4. A device, according to claim 1, wherein said tube and said ledge comprise a single unitary member whose exterior

75

shape enables it to serve as the handle of the device by the user.

5. A tube for supplying pinhooks in sequential fashion to a dispensing head attachable to either end of said tube, said tube having an interior cross section defined by the inner surface of said tube and a ledge extending longitudinal and in fixed relationship with said inner surface, said cross section conforming to the exterior periphery of said pinhooks allowing said pinhooks to supply a dispensing head connected to one of said tube ends while at the same time allowing said pinhooks to supply another dispensing head connected to said other tube end.

6. The invention defined in claim 5 wherein said ledge is integral with said inner surface and contains at least two longitudinal

dinarily extending flanges each integral with said ledge.

7. A pinhook packaging and dispensing device comprising at least one dispensing head, a tube defining an interior cross section having two ends, each end adapted for connection to one of said dispensing heads for supplying pinhooks to a connected dispensing head, said interior cross section conforming to the exterior periphery of said pinhooks allowing said pinhooks to supply a dispensing head connected to one of said tube ends while at the same time allowing said pinhooks to supply another dispensing head connected to said other tube end.
